DUNCAN S. McEWING, OF CHICAGO, ILLINOIS.

CARD FOR RAILWAY-CARS.

1,090,928.

Specification of Letters Patent. Patented Mar. 24, 1914.

Application filed June 16, 1911. Serial No. 633,483.

To all whom it may concern:

Be it known that I, DUNCAN S. McEWING, a citizen of the United States, residing at Chicago, county of Cook, State of Illinois, have invented a certain new and useful Improvement in Cards for Railway-Cars, and declare the following to be a full, clear, and exact description of the same, such as will enable others skilled in the art to which it pertains to make and use the same, reference being had to the accompanying drawings, which form a part of this specification.

One of the difficult railroad problems is the rapid disposition of freight cars so as to keep the yards clear of foreign cars and send them on their way to the road to which they belong. It is the practice to make a per diem charge against a railroad company for the full time during which a foreign car remains in its possession. A definite time is required for carrying the car on its journey from the junction point and for returning it to the junction point, and any additional time between the receipt 25 of a foreign car at a junction point and its delivery to its home road is a waste for which the road paying the per diem charge receives no valuable return.

One of the most common causes of delay is due to the inability of the yard master or clerk to determine what shall be done with a foreign car returned to his yard until he can receive the desired information through the office force of his road, this often involving considerable correspondence and often occasioning delays of many days in the case of an individual car. If a foreign car is properly marked upon its receipt at a junction point and this marking remains on the car until it has been returned to the junction point on its way home, the yard master and clerks are immediately apprised of the disposition to be made of the car when received by them and can therefore cause it to be returned to the junction point and delivered to its home road without delay, thus keeping the yards clear of dead rolling stock and saving the per diem charge which would follow if the yard masters and clerks had to obtain the desired information from the office force in the routine way.

It is customary to provide yard clerks with so-called "junction cards" which are intended to be tacked on the sides of foreign cars when received and to remain there until the car is returned to the junction point on its way home; but in actual practice very few of these junction cards are placed on the cars as intended and therefore there are always many foreign cars at junction points waiting to be returned to the road from which they were originally received.

The principal object of my invention is to produce a novel card which will make it impossible for a foreign car to start on its journey from a junction point without carrying with it data which will enable the yard masters and clerks to start the car back on its return journey, without delay, and upon the return of the car to the junction point, to send it immediately to the railroad from which it was initially received.

Before a car can be coupled into a train it must be properly carded so as to show where it is to go and therefore every car which is received at a junction point and sent on its journey must always have on it a card showing the point to which it is to be carried.

In accordance with my invention I make use of a combination card which shall take the place of the heretofore independent "final road" and "home route" or "junction" card, making it necessary for the yard clerk to place on every car the "home route" or "junction" card whenever he makes a foreign car ready to start on its journey; the arrangement being such that the "home route" or "junction" card will remain on the car after the end of the journey has been reached and the "final road" card torn off.

The various features of novelty whereby my invention is characterized will herein-after be pointed out with particularity in the claims; but, for a full understanding of my invention and of its objects and advantages reference may be had to the following detailed description taken in connection with the accompanying drawing, wherein:

Figure 1 is a plan view of one of my improved cards unfolded; Fig. 2 is a view

similar to Fig. 1 showing the card folded; Fig. 3 is a view similar to Fig. 2 of a fragment of a card showing a slight modification; Fig. 4 is a view similar to Fig. 2 showing a further modification; Figs. 5 and 6 are views similar to Fig. 2 showing still further modifications; and Fig. 7 shows a fragment of the card illustrated in Fig. 6 in its unfolded condition.

10 Referring to Figs. 1 and 2 of the drawing, 1 and 2 represent the two members of a combination card adapted to be placed on a car in a folded condition with the member 1 overlying the member 2. The 15 two portions of the cards are provided with suitably designated spaces to receive the desired data for showing the destination of a car and its home route or disposition which is to be made when it is returned to the 20 junction point. When the card is folded and tacked on a car the inscriptions on the upper member are visible and the inscriptions on the under member are rendered 25 visible when the upper member is torn away at the end of the journey for which provision is made on the upper member.

The most important use of the card is for indicating the final road and the home route of a car, but the card may also be used for the purpose of carrying data and instructions of other kinds which it is desirable to place on a car at the time of its receipt. For example, one of the members of the 35 card may be used for the purpose of carrying switching directions.

Referring again to Figs. 1 and 2 of the drawing, the card is folded along line 3, the card being preferably scored, perforated or both scored and perforated along this 40 line. Where there is scoring, this is preferably done on the inside of the fold as this permits a cleaner tear to be made across the end of the member 2 than where the scoring is on the outside. The cards are 45 made out by the office force of the railroad using them and are delivered to the yard clerk instead of the two cards which have heretofore been used. The yard clerk is compelled to place a card corresponding to 50 the member 1 on the car since otherwise the car cannot start on its journey, but heretofore there has been no means for insuring that a card corresponding to the member 2 will be attached at the same time, and 55 therefore the failure of the yard clerk to attach such a card has resulted in long expensive delays whenever a car has been returned to a junction point. Since my invention makes the two cards in one, the 60 yard clerk is compelled to fasten both cards to the car before the car can leave and therefore when the car is returned it bears directions as to the disposition to be made thereof.

The combination card is adapted to be 65 tacked to the side of a car and, in order to make it effective, it must be so constructed and so fastened that the upper member may be torn away after it has served its purpose without tearing off or injuring the under 70 card. One of the first things to guard against is the accidental tearing away of both cards when a clerk attempts to tear off the upper one. I guard against this by so constructing the two members of the 75 card that the upper member may be grasped in a natural way for tearing it off without touching the under member. This may be accomplished by making the under member smaller than the upper member, by cutting 80 away one or more corners of the under member or by adopting both of these expedients. In the arrangement shown I have made the member 2 shorter than the other and have also cut away the corners 85 of the under member at the free end thereof, as indicated at 4 and 5 so that the upper member may be grasped either at its lower end or at one of the free corners, without bringing the clerk's fingers in contact with 90 the under member.

It is necessary that the paper of cards of this kind be comparatively tough in order that it may stand up under the various weather conditions which are encountered 95 and under the wind pressure due to a rapidly moving train. The factor of toughness of the paper introduces another problem, namely that of insuring a good clean tear so as to sever the upper card without injuring the one beneath and without pulling 100 out the tacks which hold the latter in place.

One of the features of my invention consists in placing the tack which holds the two free ends of the card in such a manner that a small piece of the upper card will tear away easily and will remain as a washer between the head of the tack and the under card. This can conveniently be accomplished by cutting a short curved slit 110 6 in the member 1 at a point lying near the free end of the member 2 when the card is folded, thus forming a small tack-receiving tab. When the card is tacked through this tab and the upper member is grasped 115 at the lower left hand corner, the tab will readily tear from the body portion of the card and will leave the tack undisturbed.

I have found that simply scoring or creasing the card at the fold does not insure 120 a clean tear where the paper is tough and heavy, but the tear is apt to leave the line of the fold and pass down into the under card. In order to prevent injury to the under member in this manner I have shaped 125 the card in such a manner that the under member will be tacked securely in place and will be held firm while the upper member is

being torn away, and I further provide means for insuring the starting of the tear along the line desired. These ends may be attained by removing a portion or portions 5 of the upper member in the vicinity of the fold and slitting the card for a short distance adjacent to the cut away portion. In the arrangement shown in Figs. 1 and 2 I have cut away both of the corners of the upper 10 member adjacent to the fold, rounding off the corners thus formed on at least one side of the card as indicated at 7, 8 and 9. This leaves small sections of the under member exposed adjacent to the fold for the purpose 15 of receiving tacks and it also strengthens the upper member so that there will be no danger of tearing except at the fold which, as I have already stated, is preferably creased or scored or both creased and scored. Furthermore the upper curve 9 gradually approaches the line of fold and serves the purpose 20 of a short slit in one end of the fold, thereby making it easy to start the tear. It will be seen that the top of the under member 25 is firmly held against the car by the tacks so that there is no danger of tearing the upper end of the under card loose from the car; this firm support for the under card also insuring a clean tear along the weak- 30 ended fold.

I prefer to place suitable inscriptions such as "tack-receiving" at the three points where the tacks are to be placed.

In Fig. 3 I have shown an arrangement 35 similar to that of Figs. 1 and 2 except that the upper card member is provided with a central hole 10 near the top thereof through which a tack may be driven for the purpose of holding the under card. In Fig. 4 I have modified the device by simply rounding the upper corners of the upper card member 1^a as indicated at 11 and 12, these rounded portions 40 performing the same functions as the curve 9 in Figs. 1 and 2; the upper tacks being driven through holes 13 located in the upper member near the fold and of a size 45 sufficient to permit tacks to be driven through the under member without engaging with the overlying member.

In Fig. 5 I have shown a still further 50 modification. Both of the upper left hand corners of the two cards are cut away along a curved line as indicated at 14, this serving to direct the tear into the fold. The upper 55 card member, 1^b is provided with a hole 15 extending clear to the fold at a short distance within the left hand edge. One of the tacks may be driven into the lower card member through this hole. The corner 60 formed by the hole 15 nearest the center of the card is cut away along a curved line as indicated at 16 so that the tear will take a second start after the fold has been torn from the outer edge to the hole and will pro-

ceed cleanly across the card. The upper 65 right hand corner of the under member may be fastened in place by means of a tack driven through a tack-receiving tab formed by means of a short curved slit 17 near the upper right hand corner of the upper 70 right hand corner of the upper card member. This tab will tear away from the body portion of the card without disturbing the tack.

In Figs. 6 and 7 I have shown a still further 75 modification, the upper card member, 1^c, being provided with vertical slits 18 and 19 extending downwardly from the fold at a short distance within the sides of the car. The fold is also preferably slitted for a short 80 distance inwardly from the slits 18 and 19 as indicated at 20 and 21, the portion of the fold between the slits being preferably perforated as indicated at 22 and the remainder of the fold being perforated or creased as indicated at 23.

It will thus be seen that I have provided a simple and novel combination card which need not be more expensive than the two cards heretofore intended for the same purpose, and which will insure the placing of both cards on every car which is sent out. Furthermore the attaching of the double card requires less work and fewer tacks than is the case where two separate cards are used 90 and therefore the total expense of manufacturing and placing the double card in position is somewhat less than in the case of two individual cards so that there is here a small saving in addition to the great saving 100 which is effected by reason of the presence of both cards on every car which is sent out.

I claim:

1. A card for railway cars folded upon itself to produce two members one of which 105 is superposed upon the other, the under member having one of the corners cut away at the free end to permit one corner of the upper member to be grasped without disturbing the under member, and there being 110 suitably designated spaces on the upper face of each of said members for the reception of car data.

2. A card for railway cars folded upon itself to produce two members one of 115 which is superposed upon the other, the under member being shorter than the upper member and having one of the corners cut away at the free end, and there being 120 suitably designated spaces on the upper face of each of said members for the reception of car data.

3. A card for railway cars folded upon itself to produce two members one of which is superposed upon the other, the under 125 member being smaller than the upper member to permit the latter to be grasped at one edge without disturbing the under member,

- marks for locating tacks so arranged that at least one of the tacks placed in the positions indicated by the marks will pass through each of said members.
5. A card for railway cars folded upon itself to produce two members one of which is superposed upon the other, the under member being smaller than the upper member to permit the latter to be grasped at one edge without disturbing the under member, marks for locating tacks so arranged that at least one of the tacks placed in the positions indicated by the marks will pass through each of said members and at least 10 one of the tacks will pass through only one of said members.
5. A card for railway cars folded upon itself to produce two members one of which is superposed upon the other, the under member being smaller than the upper member to permit the latter to be grasped at one edge without disturbing the under member, the upper member having a short slit cut therein at a point above and near the 15 free end of the under member to form a tack-receiving tab.
6. A card for railway cars folded upon itself to produce two members one of which is superposed upon the other, the under member being smaller than the upper member to permit the latter to be grasped at one edge without disturbing the under member, the upper member having a tack-receiving tab cut therein at a point above the under 20 member.
7. A card for railway cars folded upon itself to produce two members one of which is superposed upon the other, the under member being smaller than the upper member to permit the latter to be grasped at one edge without disturbing the under member, the upper member only having a portion removed therefrom near the fold to permit a tack to be driven through the under member without passing through the upper member.
8. A card for railway cars folded upon itself to produce two members one of which is superposed upon the other, the under member being cut away at a point beneath one edge of the upper member so as to permit the latter to be grasped at said edge without disturbing the under member, the upper member only having at least one corner cut away adjacent to the fold to provide room for driving a tack through the under member and afford a starting point for tearing the upper member away.
9. A card for railway cars folded upon itself to produce two members one of which is superposed upon the other, the under member being smaller than the upper member to permit the latter to be grasped at the edge without disturbing the under member, the 25 upper member only having a portion removed therefrom next to the fold to permit a tack to be driven through the under member without passing through the upper member, and the corner left at the inner side by the removal of said portion being rounded gradually into the fold.
10. A card for railway cars folded upon itself to produce two members one of which is superposed upon the other, the under member being cut away at a point beneath one edge of the upper member to permit the latter to be grasped at said edge without disturbing the under member, the upper member only having at least one corner cut away adjacent to and curved gradually into the fold to provide room for driving a tack through the under member, and afford a starting point for tearing the upper member away.
11. A card for railway cars folded upon itself to produce two members one of which is superposed upon the other, the under member being cut away beneath one edge of the upper member to permit the latter to be grasped at the said edge without disturbing the under member, the upper member only having at least one corner cut away adjacent to the fold to provide room for driving a tack through the under member and afford a starting point for tearing the upper member away, and the fold being slit for a short distance adjacent to the said corner.
12. A card for railway cars folded upon itself to produce two members one of which is superposed upon the other, the under member being cut away beneath one edge of the upper member to permit the latter to be grasped at the said edge without disturbing the under member, the upper member only having at least one corner cut away adjacent to the fold to provide room for driving a tack through the under member and afford a starting point for tearing the upper member away, and the upper member also having a short curved slit cut therein above the free end of the under member to form a tack-receiving tab.
13. A card for railway cars folded upon itself to produce two members one of which is superposed upon the other, the under member being cut away beneath one edge of the upper member to permit the latter to be grasped at the said edge without disturbing the under member, there being marks for tacks located at some distance from said edge, and the upper faces of said members having suitably designated spaces for data relative to the car to which the card is to be attached.
14. A card for railway cars folded upon itself to produce two members one of which is superposed upon the other, the under member being shorter than the upper member to

permit the latter to be grasped at one edge without disturbing the under member, the upper member only having at least one corner cut away adjacent to the fold to provide 5 room for driving a tack through the under member and afford a starting point for tearing the upper member away, and the upper member also having a small tack-receiving

tab cut therein above the free end of the under member.

In testimony whereof, I sign this specification in the presence of two witnesses.

DUNCAN S. McEWING.
